UNITED STATES PATENT OFFICE.

ONESIME E. MICHAUD, OF ST. LOUIS, MISSOURI.

RAILWAY-PASSENGER MILEAGE-REGISTER.

SPECIFICATION forming part of Letters Patent No. 390,246, dated October 2, 1888.

Application filed March 19, 1888. Serial No. 267,701. (No model.)

To all whom it may concern:

Be it known that I, ONESIME E. MICHAUD, of St. Louis, Missouri, have made a new and useful Improvement in Railway-Passenger Mileage-Registers, of which the following is a full, clear, and exact description.

I have heretofore made an improvement in registers of the kind under consideration, described in my application for United States Letters Patent filed February 20, 1888, and numbered serially 264,548, and by means of which the mileages of the passengers in a railway-car are determined by a seat-adjustment and are collectively registered.

The present improvement relates to the construction referred to, and more especially to that part thereof termed the "register;" and it consists substantially in the means hereinafter set forth and claimed, and illustrated in the annexed drawings, making part of this specification, in which—

Figure 1 is a vertical longitudinal section of the improved register, the section being taken on the line 1 1 of Fig. 2, which in turn is a plan of the register mechanism, the top of the register-case being removed, and in the lower portion of the view the top part of the mechanism being removed to exhibit the mechanism beneath; Figs. 3, 4, and 5, vertical longitudinal sections on the line 3 5 of Fig. 2, and showing respectively the parts adjusted as for no registration, as for half-fare registration, and as for full-fare registration; and Figs. 6, 7, 8, and 9, details, Fig. 6 being a view in perspective of one of the pawls used in rotating the ratchet-drum, Figs. 7 and 8, respectively, an end elevation and a plan showing a portion of the cam-shaft and cams, and Fig. 9 being a view in perspective, showing the escapement in part.

The same letters of reference denote the same parts.

Those parts of the register which are constantly in motion as long as the car moves are driven from the car-axle, as in the previous construction, and it is necessary to show only that portion of the driving mechanism which is contained in the register-case—namely, the vertical shaft h^o , provided at its upper end with the bevel-gear h^{10} , which engages with the

middle pinion, i^2 , of the three bevel-pinions i^1 i^2 i^3 upon the horizontal shaft I , thereby driving the shaft I , whose motion, in turn and by means of the pinions i^1 i^3 engaging respectively with the bevel-pinion J J' , effects the rotation of 55 the cam-shafts j j' , to which the pinions J J' are respectively attached.

The register mechanism, as before, is in duplicate, dividing on the line of the shaft h^o , and the right-hand half is for use when the car is 6c traveling in one direction, and the left-hand half is for use when the car is traveling in the opposite direction. The left-hand side will be described. The cam-shaft j is provided with as many cams j^o , Figs. 2, 3, 4, 5, 7, 65 8, as there are car-seats, and they are set around the shaft j , so that no two cams project in the same plane, substantially as in the original construction. The cam-shaft j rotates continuously as long as the car is traveling forward; but, as before, the cams have no duty to perform, and they encounter no obstruction in their rotation save when the car-seats are used by a rate-paying passenger; but when a car-seat is occupied or appropriated by a rate-paying passenger—say by a half-rate passenger—the cam belonging to that car-seat is brought into use and the registration of the mileage of its passenger is effected in the following manner and by the following described means, which constitute the features of the improvement now under consideration.

F represents the cord leading from the car-seat and used in full-fare registration. It is 85 connected with a lever, K , which is pivoted at k , and at k' jointed to an upright rod, L , which can be moved vertically in or upon suitable guides, l . There is a similar cord, F , lever K , and rod L for each car-seat in the car. 90

M represents another cord leading from the car-seat and used in half-fare registration. It is connected with a lever, m , which is pivoted at m' to the lever K , so that when the cord M is drawn the lever m can be turned upon its 95 pivot m' from its position of Fig. 3 into that of Fig. 4. In this downward movement the lever m encounters a projection, m^2 , upon the lever K , and by continuing to draw the cord M the lever K is drawn downward into its po- 100

sition of Fig. 4. When the lever K is thus drawn downward, the following takes place: N represents a horizontally-disposed lever, pivoted at n to the rod L and at n' to a vertically-disposed rod, O. The lever N is drawn downward with the rod L and lever K, and the projection n^2 upon the lever N is thereby brought into the field of the cam j^2 belonging to that lever N and lever K, and the cam in its 10 rotation therefore encounters it. When the cam so encounters the projection n^2 , it operates to lift the lever N, as indicated in the right-hand portion of Fig. 4. The lifting of the lever N in turn effects the lifting of the rod O. This 15 rod O is provided with a pawl, o, Figs. 3, 4, 5, and 6, which, by reason of the interaction of the inclined part o' of the rod O and the fixed part o^2 , is brought into engagement with the ratchet-drum P, as shown in the right-hand part of 20 Fig. 4, when the rod O is lifted, and by reason of such engagement the ratchet-drum is rotated a certain distance—say the distance of one tooth—for every time the cam j^2 encounters the lever projection n^2 . The ratchet-drum 25 is fastened to its shaft p , and by transmitting the motion of the shaft p to the train Q, Fig. 2, and thence to a dial, (not shown,) the registration of the mileage is effected, as in the original construction.

30 In the case of full-fare registration the cord F is used, and when the cord is drawn the lever K is thereby drawn downward into the position of Fig. 5. This in turn causes the rod L and lever N to be drawn downward farther than when the cord M is used, and in consequence of this the end of the lever N and the rod O are lifted farther than before, and the pawl o now acts to rotate the ratchet-drum twice as far as when the cord M is used—that 35 is, a distance of two of the ratchet-drum teeth for every revolution of the cam j^2 . The drum-shaft p is therefore rotated twice as far, and the registration is correspondingly increased. The rod O works through any suitable guide. The 40 pawl o has a shoulder, o^1 , which, when the rod O is drawn upward, encounters the edge of the rod O, and is thereby held in engagement with the ratchet-drum; but when the rod O is moved downward the pawl can turn on its pivot o^5 45 and pass the ratchet-drum.

50 *The escapement mechanism.*—Pivoted to the lever N—say at the point r —is a part which may be termed a “hook,” R, which is adapted to turn upward and downward upon the point r . The hook is jointed at r' . The horizontal part r^2 of the hook is provided with the projection r^3 . The vertical part r^4 of the hook works 55 through the guides r^5 , r^6 , and the point r^7 of the hook is adapted to engage, when the hook is 60 lifted, with a bar, S. The bar S extends across the register from its front to its back, and it is shaped to form, or is provided with, the arms s , by means of which the bar is pivoted on a bearing, s' , so that the bar S can be lifted 65 and lowered through the agency of the hook R. The action of this mechanism is as follows: The cam j^2 in its rotation encounters the pro-

jection r^3 slightly in advance of the projection n^2 . The hook R and bar S are thereby lifted.

The bar S, by means of the spring s^2 , Fig. 70 9, attached to an arm, T, which at t is pivoted to the bearing s' and at t' has jointed to it the dog t^2 . The mode of attaching the bar S to the arm T is as follows: The arm T is provided with the pin t^3 , which projects 75 through a slot, s^3 , in the bar-arm s. The spring s^2 and s^4 is fastened to the arm s, and its free end s^5 bears upward against the pin t^3 . When the half-fare cord is drawn, the spring s^2 is strong enough not to yield and the arm T is 80 lifted with the bar S, and the dog t^2 thereby drawn upward out of engagement with the ratchet-drum ratchet P', leaving the ratchet-drum free to be rotated by the pawl o. The dog t^2 is provided with a shoulder, t^4 , which, 85 when the dog is lifted, encounters the stop t^5 , and the upward movement of the dog is thereby limited; but when the full-fare cord is drawn the spring s^2 yields, after the dog encounters the stop t^5 , and the bar S is drawn 90 upward above the outer part of the arm T, by which movement the pin t^3 comes to the lower end of the slot s^3 . As soon as the hook R is released, the spring t^6 acts to draw the arm T downward and to bring the dog t^2 into engagement again with the ratchet P', as shown 95 in the left-hand portion of Fig. 5, and the ratchet-drum is thereby prevented from being carried around too far under the impulse of the pawl o. When the bar S is drawn upward, as described, above the arm T, the spring s^2 co-acts with the spring t^6 in bringing the dog t^2 into engagement with the ratchet.

Another feature of the construction is the stop mechanism E. Figs. 3, 4, and 5 represent a horizontally-disposed bar adapted to be moved longitudinally toward and from the rod O. The rod L is at each side thereof provided with an inclined arm, l^1 , which engages in a slot, e , in the bar E, so that when the half-fare 105 cord is drawn the movement of the rod L has no effect upon the bar E, and the rod O is free to be lifted until the extension o^5 of the rod O encounters the bar E, whereupon the rod O is arrested. This is arranged so that the rod O 110 is raised sufficiently to cause the ratchet-drum to be rotated a distance of one tooth; but when the full-fare cord is used the rod L, through its arm l^1 , acts to draw the bar E out of the field of the rod O, whereupon the rod O can 120 be lifted until the rod-extension o^5 encounters the stop o^{10} , which is so arranged that the rod O, when it is arrested by the stop o^{10} , is raised 125 sufficiently to cause the ratchet-drum to be rotated a distance of two teeth.

To relieve the friction, the cams are each, at the point at which the cam encounters the projections r^3 , n^2 , provided with a roller, as shown.

I claim—

1. The combination of the rod L, the lever N, projection n^2 , the cam-shaft j , and cam j^2 , as and for the purpose described.

2. The combination of the rod L, the lever

130

125

N, projection n^2 , the cam-shaft and cam, the rod O, the pawl o, and the ratchet-drum P, substantially as described.

3. The combination of the rod O, the inclined part o' , vertically upon said rod, the fixed part o^2 upon the frame, the pawl o, and the ratchet-drum P, substantially as described.

4. The combination of the rod L, the lever N, having the projection n^2 , the rod O, parts $o' o^2$, the pawl o, and the ratchet-drum P, said parts $o' o^2$, respectively, being vertically upon said rod O and fixed upon the frame, substantially as described.

5. The combination of the half-fare cord, the levers m K, and the rod L, said lever K being provided with the projection m^2 , substantially as described.

6. The combination of the hook R, the bar S, the spring s^2 , the arm T, the dog t^2 , and the ratchet P', substantially as described.

7. The combination of the slotted bar S, the

bearing s' , the arm T, the pin t^3 , and the spring s^3 , substantially as described.

8. The combination of the slotted bar S, the bearing s' , the arm T, the pin t^3 , the spring s^3 , 25 the dog t^2 , having the shoulder t^4 , the stop t^5 , and the spring t^6 , substantially as described.

9. The combination of the rod L, the lever N, projection n^2 , the hook R, the projection r^3 , the cam-shaft and cam, the rod O and pawl o, 30 the ratchet-drum P, and ratchet P', attached to said drum, the bar S, the arm T, and the dog t^2 , substantially as described.

10. The combination of the rod L, inclined arm t^5 , the slotted bar E, and the rod O, having the extension o^3 , substantially as described. 35

Witness my hand this 17th day of March, 1888.

ONESIME E. MICHAUD.
